6 Claims. (Cl. 274—39)

In order to obtain a musical reproduction of a high quality from a musical recording on record, it is necessary that the fluctuations of the rotation speed of the record about its average speed do not exceed 1 to 2% of this average speed.

Now, the devices for driving in rotation the record from the turn-table motor, which may comprise gearings, friction devices or any other means, always provoke speed fluctuations because of the very small mechanical imperfections, which the most accurate machining cannot eliminate entirely. In order to equalize these fluctuations and to deaden their amplitude, the speaking machine manufacturers provide their machines with very heavy turn-tables having a great inertia.

Furthermore, in order to obtain a very weak background noise level during the reproducing of a record, it matters to reduce in all the possible measure the transmission of vibrations to the pick-up device and to the record itself. To this aim, one seeks to mechanically isolate the motor with respect to the machine frame by means of deadening devices. These devices are the more efficient the more the motor is light with respect to the whole machine.

The vibrations of the motor of electrical or mechanical origin are, on the other hand, the more difficult to master the more powerful this motor is. For these various reasons, one aims at giving the preference to a motor of a low power having a light weight and driving a turn-table of great inertia.

In order to obtain nevertheless an extremely rapid stabilisation of the record speed to its nominal value at starting time, a characteristic which allows the laying of the very sensitive pick-up onto the motionless record without appearing of disagreeable tune variations at the beginning of the hearing, some manufacturers have proposed to provide a turn-table driving device comprising a coupling located between the turn-table and the record to be driven. Thus, the motor and the turn-table of great inertia can be maintained in permanent rotation, whereby solely the mechanical connection between said turn-table and said record being interrupted or re-establish at will. The devices of this type known up to now, are provided with various coupling devices. The most used one comprises an auxiliary washer pivoted on the turn-table shaft and resting on said shaft by means of felt strips. The record to be played is laid onto the upper face of this washer coated with felt or rubber. For stopping the record, it is sufficient to hold back the washer either manually or by means of a peripheral brake.

Still the experience shows that, despite the very small weight of such a washer and of the record laying on said washer, the frictions between the turn-table and said washer, when said washer is stopped, are sufficient to slacken the speed of the turn-table of great inertia down to such a value that a further rapid starting becomes impossible. One must then provide a much more powerful motor with the above mentioned disadvantages.

2

To remedy to this drawback, one has recommended a coupling which, in the disengaged position, suppresses the greater part of the frictions between the auxiliary washer and the turn-table of a great inertia.

5 If it is not desired to foresee intricate devices already known, one is brought to cause an axial displacement, either of the auxiliary washer or of the turn-table, in order to bring them from an engaged position to a disengaged one. Thus, it has been recommended to control 10 the axial displacements of the auxiliary washer by means of a rod coaxial with the turn-table revolving axis and going through a hollow shaft carrying said turn-table.

Now, in addition to the manufacturing difficulties, such hollow shafts do not allow to make use of the only thrust bearing which has the best performances and is fully satisfying for carrying a turn-table of great inertia: an only ball resting on the end of the shaft rotating on a plate made out of a special material such as "nylon." The ball bearings and peripheric smooth thrust bearings do not enable to realize, by mass production, a bearing quality which would satisfy the very high requirements for high quality speaking machines, the frictions between the turn-table and the fly-wheel, the speed of this fly-wheel do not undergo, at the stopping of the turn-table, such a speed reduction, as to cancel all the advantages sought by this coupling device.

The present invention has for its object a driving device of the turn-table of a speaking machine, which comprises a coupling device connecting a fly-wheel to said turn-table and an actuating device of said turn-table causing an axial displacement of said turn-table along a centering member and the interruption of the mechanical connection connecting said fly-wheel to said turn-table. Said device distinguishes from the known devices by the fact that said actuating device comprises an actuating member pivoted with respect to the frame of the speaking machine and disposed between the upper face of said frame and the under front face of a peripherical flange of said turn-table.

40 The attached drawings show schematically and by way of example a form of execution of the coupling device according to the invention.

Fig. 1 is a partial cross section along line I—I of the Fig. 2.

45 Fig. 2 is a top view.

Fig. 3 is a partial cross section at a greater scale along line III—III of the Fig. 2.

Fig. 4 is a partial cross section at a greater scale of a detail.

50 In the attached drawings, only the members and parts of the talking machine necessary to the good understanding of the coupling device object of the present invention have been represented.

55 The frame 1 of the speaking machine bears a bearing 2 fixed by bolts 3 and within which rotates freely a shaft 4 onto which is fastened a fly-wheel 5 of a sufficient great inertia for the absorption of the speed variations due to mechanical or electrical causes. The shaft 4 bears by the intermediary of a thrust ball 6 on a plate 7 fastened to the bottom of the bearing 2, by screws 8.

60 The fly-wheel 5, preferably made of cast iron, is fixed by bolts 9 on a collet 10 of the shaft 4.

65 In order to increase the inertia of the fly-wheel 5, the greater part of its material is distributed along its periphery which has a circular flange 11, the internal cylindrical surface 12 of which is accurately machined. Said cylindrical surface, accurately centred with respect to the shaft 4, is in frictional contact with a frictional driving member (not shown) as described and represented, for example, in the U.S. application No. 686,505 of September 26, 1957.

A turn-table 13, preferably made of a light alloy such as aluminium, is driven in the rotation of the fly-wheel 5 by a friction coupling constituted, on the one hand, by felt strips 14 glued on the upper face of the fly-wheel 5, and, on the other hand, by a circular rib 15 of the turn-table 13 and protruding with respect to its under face. This turn-table is axially movable along a centering pin 16 carried by the shaft 4 and presents a peripherical flange 17 which covers the peripherical rim of the fly-wheel 5 and extends by some millimetres lower than the under face of said rim. The turn-table 13 has a dished central part 19 engaged into a central housing 20 provided in the fly-wheel 5. A circular piece 21 having the general form of a cup provided with a rim 22 is fastened by screws 23 inside the bottom of the dished part 19. Between the rim 22 of said circular piece 21 and the turn-table 13 is pinched a washer 24, made of rubber, synthetic material or of felt, provided for supporting the phonographic record (not shown).

In the inside of this cup 21 is mounted a centering part 25 having the general shape of an over-turned cup. The diameter of said centering part 25 corresponds to the diameter of the central bore of a 6 1/2 in. record provided with a large central bore. The diameter of the pin 16, on the contrary, corresponds to the diameter of the central bore of the various records provided with a small central bore. This centering part 25, submitted to the action of a spring 26, slides along the pin 16 and is able to occupy the two following positions:

(a) A withdrawn position in which its upper face 27 is located in the plane of the surface 28 of the washer 24. This part 25 takes automatically said withdrawn position under the action of the weight of a record to be played having a small central bore, laid onto the washer 24;

(b) A raised or working position in which it projects out of the surface 28. An operating member 29 having the shape of an arc of circle carries:

(a) A pivot 30 revolving in a hole provided in the frame;

(b) A pin 31 passing through a guiding port 32 provided in the frame. Springs 33 (Fig. 3), bearing on the frame under face and exerting a push onto washers 34 carried by the pin 31 and the pivot 30, tend to maintain the operating member 29 in its rest position (shown on Fig. 1);

(c) A control member 36 protruding laterally with respect to the turn-table;

(d) Three bores 37 located approximately at 90° one to another.

The frame 1 is provided with three gudgeons 39, each of which having a countersink provided in its upper front face 40, located in the plane of the upper face 41 of the frame. A ball 42 is housed within each of these counter-sinks. The working of the described speaking machine is the following:

When the control member 36 is set in the position A, the part 29 takes the position shown in full lines in the Fig. 2. For this position, the bores 37 provided in this part 29 correspond to the balls 42, so that under the action of the springs 33, this part 29 takes a rest position, shown on the Fig. 1, in which the balls 39 enter into these bores 37, so that the under face of said part 29 comes to lay onto the upper face 41 of the frame. The turn-table 13 is then laying by the intermediary of the circulator rib 15 onto the felt strips 14, so that said turn-table is driven in rotation by the friction of the rotating fly-wheel 5.

On the contrary, by operating the operating member 36 from the position A up to the position B, the part 29 pivots on the pivot 30, the pin 31 slides in the guiding port 32, and the balls 42 co-operating with the edge of the bores 37 provoke a lifting movement of the part 29. During its displacement said part 29 comes into contact with the under front face of the flange 17 and lifts the turn-table 13. Consequently the circular rib 15 leaves the felt strips 14, as shown on the Fig. 4, so that the me-

chanical connection between the turn-table 13 and the fly-wheel 5 is interrupted. This turn table stops although the fly-wheel continues to be driven in rotation.

For the hearing of a gramophone record, the operator put the record onto the washer 24, places the control member 36 in the position B and put the motor of the machine under voltage.

The fly-wheel 5 is then driven in rotation while the record to be played stay motionless. When said fly-wheel has reached its nominal speed and that this speed has stabilized, the operator put the pick-up onto the gramophone record to be played, which is still motionless, then operates the control member 36 up to the position A, in order to set up a mechanical connection between the turn-table 13 and the fly-wheel 5 and thus the driving in rotation of the turn-table 13 and of the record to be played. The mass of the turn-table 13 and of the record to be played being a light one with regard to the mass of the fly-wheel 5, the provoked perturbation is a small one, so that the rotation speed of the set, comprising the fly-wheel 5, the turn-table 13 and the record to be played is very quickly stabilized, during 1/3 or 1/2 revolution, at the nominal speed.

The described coupling device is of a very simple conception and enables, when it is in the disengaged position, to suppress practically all the frictions between the driving part and the driven part. Consequently the fly-wheel 5 can be driven by a low power motor, merely sufficient to maintain the speed stability of said fly-wheel 5 running free.

Furthermore, the turn-table 13 made of aluminium has still an additional advantage that cannot be neglected. Indeed, it practically suppresses entirely the influence which may exert on a magnetic pick-up, having a high dispersive flux, the ferro-magnetic mass of the fly-wheel 5. Consequently, it is not necessary to provide a fly-wheel made of aluminium, the sizes of which could become very large and the cost price very high, if one desires to obtain a sufficient fly-wheel effect.

In the device according to the invention, one may foresee a fly-wheel 5 made of cast iron, which thanks to its high material specific weight, its machining easiness, its stability of dimensions and its low cost price, presents great advantages with regard to a turn-table of aluminium working as fly-wheel, without still being prejudicial to the quality of the musical reproduction. The playing surface of the record is effectively sufficiently distant from the ferromagnetic mass of the fly-wheel 5, so that the influence of this mass onto a magnetic pick-up can be entirely neglected.

Lastly, the peripherical surface of the flange 17 can easily be polished, so as to give a fine sight to the entire driving device of the gramophone record.

A form of execution of the turn-table driving device, object of the invention, has been described here and by way of example and with reference to the attached drawings, but it is clear that multiple variants can be foreseen. Thus, for example, the balls 42 and the corresponding bores provided in the operating member 29 could be replaced by any other operating means enabling to provoke an axial displacement of the operating member at the time of its manual operation in an angular displacement round its pivot 30. Such operating means could, for example, be constituted by wedges fastened to the frame and to the operating member 29 and co-operating one with another.

I claim:

1. In a phonograph comprising a frame, a turntable having a depending peripherical flange, a motor, a fly-wheel driven in rotation by said motor, a centering member of said turntable and a friction coupling connecting said turntable to said flywheel, the combination of an actuating device comprising an arcuate actuating member pivoted on said frame of said phonograph and displaceable from a rest to a working position, said

actuating member being located between the upper surface of said frame and the lower front surface of said peripheral flange of said turntable, means carried by said actuating member, said actuating device comprising further means carried by said frame, said means carried by said frame engaging said means carried by said actuating member when said actuating member is in its rest position and abutting against the lower surface of said actuating member when it is located in its working position, whereby said turntable rests on said flywheel and is driven in rotation by said flywheel through said friction coupling when said actuating member is in rest position and on the upper surface of said actuating member when it is in its working position, disconnecting said turntable from said flywheel and maintaining said turntable in a fixed axial position.

2. A phonograph according to claim 1 and in which said means carried by said actuating member are constituted by openings made in said actuating member, and in which further said means carried by said frame comprises housings made in said frame and balls located in said housings.

3. A phonograph according to claim 1 and in which said friction coupling comprises a circular rib provided on the under surface of said turntable, and supple pieces having a high friction coefficient located on the upper surface of said flywheel, said turntable resting on said flywheel by the intermediary of said rib and said supple pieces.

4. In a phonograph comprising a frame, a flywheel of large inertia revolving in a bearing secured to said frame, a turntable of smaller inertia coaxially mounted on the upper surface of said flywheel, centering means in said flywheel for said turntable, friction coupling means on said flywheel for said turntable, the outer edge of said turntable having a depending peripheral flange larger than the edge of said flywheel, the combination of a plurality of lifting means angularly disposed under the outer edge of said turntable and mounted on said frame for reciprocal movement between a rest position in which they are out of contact with said outer edge of said turntable and a lifted position in which they are engaging and lifting said turntable by its outer edge for disconnecting said turntable from said flywheel and maintaining it in a fixed axial position, and a manually-actuated control member mechanically connected to said lifting means to simultaneously move them between their rest and their lifted positions.

5. In a phonograph comprising a frame, a flywheel of large inertia revolving in bearing means in said frame, a turntable of smaller inertia coaxially mounted on the upper side of said flywheel, centering means in said flywheel for said turntable, friction coupling means on said

flywheel for said turntable, the outer edge of said turntable having a depending peripheral flange larger than the edge of said flywheel, the combination of a manually-actuated control member pivoted on said frame for angular and axial movement about an axis substantially parallel to the axis of said flywheel, a plurality of lifting means on said control member angularly disposed under the outer edge of said turntable, cam means on said frame and on said control member adapted to 10 transform an angular displacement of the control member and an axial displacement of the same from a rest position in which said lifting means are out of contact with said outer edge of said turntable to a lifted position in which said lifting means are engaging and lifting said turntable by its outer edge for disconnecting said turntable from said flywheel and maintaining it in a fixed axial position.

6. In a phonograph comprising a frame, a flywheel of large inertia revolving in a bearing in said frame, 20 a turntable of smaller inertia coaxially mounted on the upper side of said flywheel, centering means in said flywheel for said turntable, friction coupling means on said flywheel for said turntable, the outer edge of said turntable having a depending peripheral flange larger than the edge of said flywheel, the combination of a control member formed as a substantially semi-circular shaped lever and disposed in a substantially coaxial position, underneath and parallel to the outer edge of said turntable, said control member being pivoted 25 for angular and axial movement on said frame about an axis parallel to the axis of said flywheel, manually-actuated means on said control member for controlling the angular displacement of this latter, stop means in said frame determining two angular end positions of 30 said control member, cam means in said frame and in said control member adapted to transform the angular displacement of the control member to an axial displacement of the same from a rest position in which said control member is out of contact with said outer edge of said turntable and a lifted position in which said control member is engaging and lifting said turntable by its outer edge for disconnecting said turntable from said flywheel and maintaining it in a fixed axial position.
